UNITED STATES PATENT OFFICE

146,183

DESIGN FOR A REMOTELY CONTROLLED TARGET AIRPLANE

Neill F. McGaffey, Inglewood, Calif., assignor to
Radioplane Company, Van Nuys, Calif., a cor-
poration of California

Application October 29, 1945, Serial No. 123,292

Term of patent 14 years

(Cl. D71—1)

To all whom it may concern:

Be it known that I, Neill F. McGaffey, a citizen of the United States and resident of Inglewood, in the county of Los Angeles and State of California, have invented a new, original, and ornamental Design for Remotely Controlled Target Airplane, of which the following is a specification, reference being had to the accompanying drawings, forming part thereof.

Fig. 1 is a perspective view of a remotely controlled target airplane showing my new design;

Fig. 2 is a side elevational view;
Fig. 3 is a plan view;
Fig. 4 is a front elevational view; and
Fig. 5 is a bottom view thereof.

I claim:

The ornamental design for a remotely controlled target airplane, as shown.

NEILL F. McGAFFEY.
